UNITED STATES PATENT OFFICE.

ALONZO EDWARD RHODES, OF HILLCREST, DELAWARE, ASSIGNOR TO TURNSTILE AND REVOLVING DOOR COMPANY, OF WILMINGTON, DELAWARE, A CORPORATION OF DELAWARE.

TURNSTILE.

1,280,550.

Specification of Letters Patent.

Patented Oct. 1, 1918.

Application filed February 15, 1917. Serial No. 148,746.

To all whom it may concern:

Be it known that I, ALONZO EDWARD RHODES, a citizen of the United States, and a resident of Hillcrest, Delaware, have invented certain Improvements in Turnstiles, of which the following is a specification.

The object of my invention is to provide a simple form of turnstile, arranged for movement in one direction only; being normally locked against movement in either direction, and provided with suitable releasing means whereby it may be readily placed in condition to move in one direction as desired. A further object of my invention is to construct a turnstile designed to move in one direction only in such manner that reversal of a part of the structure permits a change in the direction of its movement; in one position being a right hand turnstile and in another position a left hand turnstile. If desired, I may combine a suitable registering device with the turnstile.

These and other features of my invention are more fully described hereinafter, reference being had to the accompanying drawings, in which:

Figure 1, is an elevation, partly in section, of one form of turnstile made in accordance with my invention.

Figs. 2, 3 and 4, are sectional plan views on the lines II—II; III—III, and IV—IV, respectively, Fig. 1, and

Fig. 5, is a sectional elevation illustrating a modified construction within the scope of my invention.

In the drawings, a pedestal mount for the turnstile structure is shown at 1, which may comprise a hollow base 2, secured in position by any suitable means, and a head 3 which may be integral therewith. The lower part of the head is provided with a shoulder 4, and its upper end has a bearing flange 5.

Mounted upon the head of the pedestal is a tubular shell or casing 10, carrying a plurality of arms 11; such shell or casing having a flange 12 adapted to the shoulder 4 of the base, and an internal flange or shoulder 13 adapted to engage the bearing flange 5 at the upper end of the pedestal head 3.

Pivottally mounted in a slot 3^a in the head 3 is a gravity pawl 15 adapted to engage ratchet teeth 16 formed in a flange or shoul-

der 17 carried by the shell 10 to prevent backward movement of said shell with respect to the head. Below the flange or shoulder 17, a third flange or shoulder 18 is disposed on the inner wall of the casing 10, having four teeth 19 for engagement with the end of a catch-bar or locking member 20 vertically mounted and movable within the base of the pedestal, with its upper end disposed in a slot 3^b in the head 3. This catch-bar is preferably a gravity-operated structure, and may be connected at its lower end 21 to a foot lever 22 pivoted at 23 to the pedestal base. In its normal, lowered, position, this catch-bar lies with its upper end in engagement with one of the teeth 19 to prevent movement of the shell 10 journaled on the head 3 at the upper end of the pedestal by engagement with its arms 11. Means are preferably provided for guiding the upper end of the catch-bar or locking member 20, and such means, in addition to the slot 3^a in the head 3, may comprise positioning screws 24 and 25, carried by the pedestal 1 and disposed in engagement with the catch-bar at front and back of the same.

When it is desired to permit operation of the turnstile to admit a person, the operator presses down upon the foot lever 22, thereby raising the upper end of the catch-bar from engagement with one of the teeth 19 and the turnstile is free to move in one direction, depending upon the position of the teeth engaged by the pawl 15. Should it be desired to lock the catch-bar out of action so that the turnstile can be moved continuously, in one direction of course, I provide a pin 26 adapted to hold the foot lever when lowered to the housing 27 of the base in which it is journaled and thereby maintain the catch-bar in the raised, inactive position.

It will be understood, of course, that the position of the ratchet teeth 16 and 19 within the shell 10 determines the direction of movement of the casing 10 and the arms 11, and that in order to provide right-hand and left-hand turnstiles, it is necessary to provide the respective casings with ratchet teeth 16 and 19 facing in opposite directions, respectively. For this purpose, the said ratchet teeth 16 and 19, or their equivalent, faced in the desired direction, may be carried by removable members which may

be set as desired in the casing; depending entirely upon the direction the arms of the turnstile are to move, and fixed in such position to the flanges 17 and 18 for proper coaction with the pawl 15, and locking member 20.

In some instances, it may be desirable to provide a complete rotatable structure available for use in turnstiles to be moved to the right or left, as the circumstances of placing such structures may require. To this end, I may provide a casing such as shown at 10* in Fig. 5, having sets of ratchet teeth at top and bottom of the same; in one of which sets the respective teeth lie in one position, and in the other of which the teeth lie in the opposite position, respectively.

In this arrangement, the flanges 17 and 18 at the bottom of the casing carry teeth 16 and 19, while the flanges 17^a and 18^a, shown as disposed at the top of the casing, carry teeth 16^a and 19^a, respectively. The mechanism of the turnstiles shown in Figs. 1 and 5, is so arranged that the arms 11 must be moved to the left, or clock-wise. By reversing the casing shown in Fig. 5, with respect to the head 3, the ratchet teeth 16^a and 19^a will be in position to permit the arms of the turnstile to move to the right, or counter clock-wise when the locking member 20 is lifted or released from its engagement with one of the teeth 19. In the structure shown in Fig. 1, a special flange 13 is provided for engagement with the bearing flange 5 of the head. In the arrangement illustrated in Fig. 5, the flange 17^a engages said bearing flange.

Should it be necessary or desirable to ascertain the number of persons passing through the turnstile, the head 3 of the pedestal may be provided with a suitable registering device, the casing of which is indicated at 28 and as secured to the bearing flange 5, and having an operating arm 29 extending outside said casing and adapted to be acted upon by lugs 30 preferably arranged in line with the external arms 11 carried by the shell 10 and disposed on the inner wall of the same. The top of the shell 50 or casing 10 may have a glass plate 31 so that the numbers of the registering device may be readily viewed.

In the arrangement shown in Fig. 5, an extra flange is provided at the top of the casing, 18 or 18^a, depending which end of the casing is uppermost; such flange being disposed with its ratchet teeth, 19 or 19^a, inverted with respect to said counting device. These teeth may be employed as the means for actuating the counter; the latter being provided with an operating arm 29^a extending upwardly for contact therewith and engaged successively by the four teeth. The flange which receives the glass plate 31 in the construction shown in Fig. 5, will

rest on the shoulder 4, when the casing 10 is reversed.

I claim:

1. In a turnstile, the combination of a pedestal having a head, a cylindrical casing rotatable on said head and carrying passage-barring arms, a plurality of sets of ratchet teeth disposed on the inner wall of said casing, a vertically movable catch-bar for engagement with one set of said teeth, means for lifting said catch-bar from engagement with said teeth, and a pawl carried by the head for engagement with a second set of teeth disposed above the catch-bar engaging teeth to prevent movement of said casing in more than one direction. 80

2. In a turnstile, the combination of a pedestal having a slotted head, a cylindrical casing rotatable on said head and carrying passage-barring arms, a plurality of sets of ratchet teeth disposed on the inner wall of said casing, a vertically disposed catch-bar movable in the slotted head and adapted to engage said teeth, a foot lever for lifting said catch-bar from its engagement with said teeth, a pawl carried by the head in engagement with a second set of teeth for preventing movement of said casing in more than one direction, and means for adjusting and guiding the catch-bar in the pedestal. 95

3. In a turnstile, the combination of a pedestal having a head, a cylindrical casing rotatable on said head and carrying passage-barring arms, a plurality of sets of ratchet teeth disposed on the inside of said casing, a vertically movable catch-bar for engagement with one set of said teeth, a foot lever for releasing said catch-bar, and a gravity-actuated pawl carried by the head in engagement with the other set of teeth and normally in action to prevent movement of said casing in more than one direction. 100

4. In a turnstile, the combination of a pedestal having a head, a cylindrical casing having flanges whereby it may be rotatably journaled on said head, passage-barring arms carried by said casing, a plurality of sets of ratchet teeth disposed on the inside of said casing, a vertically movable catch-bar for engagement with one set of teeth, a foot lever for elevating and releasing said catch-bar, means for holding said catch-bar in the elevated position, a pawl carried by the head for engagement with the other set of teeth and normally in action to prevent movement of said casing in more than one direction, and adjustable screws for guiding the catch-bar in its vertical movements in the pedestal. 115

5. In a turnstile, the combination of a pedestal and its head, a rotatable casing carried by said head, a pawl carried by the head to prevent backward movement of the casing, a locking member to prevent operation of the casing, and pluralities of sets 120

130

of ratchet teeth for engagement respectively with said pawl and said locking member; said sets of teeth lying in paralleling planes disposed in opposite directions whereby the 5 casing is susceptible of reversal with respect to the head of the pedestal to provide right and left-hand turnstiles.

6. In a turnstile, the combination with a pedestal and its head, of a rotatable casing 10 carried by said head, a gravity pawl carried by the head to prevent backward movement of the casing, a locking member vertically movable in the casing to prevent rotation of the same, and two sets of ratchet teeth for 15 engagement respectively with said pawl and said locking member; said sets of teeth lying in such position that the casing is susceptible of reversal with respect to the head of the pedestal to provide right and left-hand turn- 20 stiles.

7. In a turnstile, the combination of a pedestal having a head, a cylindrical casing rotatable on said head and carrying passage-barring arms, ratchet teeth disposed on the 25 inside of said casing, a vertically movable catch-bar for engagement with said teeth, means for lifting said catch-bar from engagement with said teeth, an independent set of teeth carried by said casing, a pawl 30 carried by the head for engagement with said second set of teeth to prevent movement of said casing in more than one direction, and a second set of teeth lying in opposite positions with respect to the first set and 35 providing a reversible casing for right and left-hand turnstiles.

8. In a turnstile, the combination of a pedestal having a slotted head, a cylindrical casing rotatable on said head and carrying 40 passage-barring arms, ratchet teeth disposed on the inside of said casing, a vertically movable catch-bar movable in the slotted head and adapted to engage said lugs, a foot lever for lifting said catch-bar from its en- 45 gagement with said teeth, an independent set of ratchet teeth carried by said casing, a pawl carried by the head in engagement with said last named teeth for preventing movement of said casing in more than one 50 direction, means for guiding the catch-bar in the pedestal, and a second set of teeth lying in opposite positions with respect to the first set and providing a reversible casing for right and left-hand turnstiles.

55 9. In a turnstile, the combination of a pedestal having a head, a cylindrical casing rotatable on said head and carrying passage-barring arms, a plurality of sets of ratchet

teeth disposed on the inside of said casing, a vertically movable catch-bar for engagement 60 with one set of said teeth, a foot lever for releasing said catch-bar, a gravity-actuated pawl carried by the head in engagement with the other set of teeth for preventing movement of said casing in more than one 65 direction, and a plurality of sets of other teeth lying in opposite positions with respect to the first set and providing a reversible casing for right and left-hand turnstiles.

10. In a turnstile, the combination of a 70 pedestal having a head, a cylindrical casing having flanges whereby it may be rotatably journaled on said head, passage-barring arms carried by said casing, and means for limiting the rotative movement of the casing; said casing having duplicate limiting means whereby it may be reversed on the head. 75

11. In a turnstile, the combination of a pedestal and its head, and an invertible cas- 80 ing rotatably carried by said head and having passage-barring arms.

12. In a turnstile, the combination with a pedestal and its head, of an invertible casing 85 rotatably carried by said head and having passage-barring arms, means to prevent movement of the casing, and means for releasing the same.

13. In a turnstile, the combination of a pedestal having a head, a cylindrical in- 90 vertible casing rotatable on said head and carrying passage-barring arms, a plurality of sets of ratchet teeth disposed on the inside of said casing, a vertically movable catch-bar for engagement with said teeth, means 95 for lifting said catch-bar from engagement with said teeth, and a pawl carried by the head for engagement with a second set of teeth disposed above the catch-bar engaging teeth to prevent movement of said casing in 100 more than one direction.

14. In a turnstile, the combination of a pedestal, a head carried thereby, a reversible casing rotatably carried by said head, pas- 105 sage-barring arms carried by said casing, a plurality of sets of ratchet teeth carried by the casing and interiorly disposed, a pawl carried by the head for engagement with one set of ratchet teeth when the casing is in either position, a locking bar for engagement with another set of ratchet teeth when the casing is in either position, and means for releasing said locking bar. 110

In witness whereof I affix my signature.

A. EDWARD RHODES.
